PRESSURE DISPENSING VALVE ACTUATOR

Abe O. Samuels, Bridgeport, Conn., assignor, by
mesne assignments, to Maryland Devices, Inc.,
Baltimore, Md., a corporation of Maryland

Application June 16, 1950, Serial No. 168,460

6 Claims. (Cl. 222—394)

1

This invention relates to attachments which may be secured to pressure-tight containers over the discharge valves thereof and by which the valves may be easily operated without the fatigue which is now incurred, particularly when they must be operated for any substantial period of time.

Most of the discharge valves currently employed with self-dispensing pressure-tight containers are of the type which employ a simple spring urged reciprocable valve mechanism operable by the application of pressure to the top of a portion of the discharge valve which extends above the upper end of the pressure-tight container. The discharge valves are normally very small, at least when compared with the size of a normal user's finger, and because of this, the force required to open the valve against the pressure of the spring as well as against the pressure of the contents of the container is a very fatiguing one to assert either continuously or intermittently for a long period of time. Additionally, the discharge valve, because of the characteristics above set forth, cannot normally be easily controlled to discharge the container contents evenly or at various uniform rates. That is, it is very difficult to maintain the discharge valve open at any but its wide-open position.

My invention contemplates the provision of an attachment which may be secured over the discharge valve of a self-dispensing pressure-tight container to remove the aspect of fatigue from the operation of the discharge valve and which permits a fine control of the valve at any position between fully closed and fully opened positions. To this end, it comprises simply a cover member adapted to be removably secured to the container over the discharge valve, and a trigger, the major portion of which is freely supported within the cover member and has one end extending through an opening in the cover member so that it may be engaged by the user's finger. With the attachment in place on a container, the inner end of the trigger is advantageously freely supported by an immovable part of the discharge valve or of the container and extends across the top of the discharge valve. The inner end of the trigger is prevented from moving upwardly by engaging the rim of the discharge valve supporting member of the container or by being in close proximity to the inner face of the top of the cover member. The opening in the cover member through which the other end of the trigger extends is sufficiently large to permit movement of that end of the trigger and, when it

2

is moved downwardly, pressure is applied to the top of the discharge valve because, as stated, the inner end of the trigger cannot move upwardly. Thus, the discharge valve is opened and the contents of the container are discharged. It is the extent to which the outer end of the trigger is depressed by the user's finger which determines the extent to which the discharge valve is opened and thereby the rate at which the container contents are discharged. The leverage provided by the trigger makes the operation of the discharge valve fairly easy, requiring less pressure from the user's finger and thereby making the operation less fatiguing. This leverage also permits finer control of the valve.

Some means or other is provided to prevent the trigger from sliding longitudinally in the opening in the cover when the cover is secured to the container, this means being, most advantageously, a downwardly extending lip punched or stamped out of the trigger to prevent sliding of the trigger by engaging the lower edge of the opening in the cover member through which the trigger extends.

25 Two forms of attachment, which come within the scope of my invention, will be more specifically described in conjunction with the accompanying drawing in which:

Fig. 1 is a plan view, partly broken away, of the preferred form of my novel attachment mounted on a pressure-tight container which is provided with a discharge valve,

Fig. 2 is an elevational view, in section, taken along line 2—2 of Fig. 1,

Fig. 3 is a perspective view of the preferred form of trigger, and

Fig. 4 is a fragmentary elevation, in section, of an attachment including a modified form of trigger.

30 By reference to the drawings, one type of pressure-tight container with which the valve-actuating trigger mechanism may be suitably and advantageously used comprises a side wall 10, a top wall 11 terminating in an upwardly extending curved flange 12, and a discharge valve supporting member or container top 13. Member 13 is provided with a curved peripheral flange or rim 14 adapted to interengage flange 12 of the container top to seal the container closed. The flange or rim 14 has an underlying portion 14'. A discharge valve 15 of the type disclosed and claimed in my copending application Serial No. 161,835, filed on May 13, 1950, is mounted in an opening 16 in member 13. A portion of this valve 35 extends above the container and terminates in

an inturned peripheral flange 17 which secures a flexible diaphragm 18 across the top of the valve and over a valve actuating member or button (not shown) by which the valve mechanism (not shown), contained within the valve, may be operated. A siphon tube 19 is connected to a portion of the discharge valve which lies within the container and extends downwardly toward the bottom of the container so that all the contents thereof may be discharged. The discharge valve also includes a discharge nozzle 20 through which the contents of the can are discharged when the discharge valve is operated by depression of the flexible diaphragm 18.

My valve-actuating trigger attachment comprises a dome-shaped cover member 22 having a downwardly extending curved peripheral flange 23 which fits tightly about interengaging flanges 12 and 14 of the container to removably secure it to the container. A portion of the cover member 24 is depressed and contains an opening 25 which is so located that nozzle 20 of the discharge valve may discharge through it. The upper part 26 of this depressed portion 24 of the cover member lies close to the wall of the upper part of the discharge valve just above the nozzle. Diametrically opposite depressed portion 24 is a second depressed portion 27 of the cover member at the upper part of which is formed an opening 28.

A trigger 30 is freely mounted within the cover member and has one end 31 extending outside of the cover member through opening 28 therein, thereby being adapted to be engaged by a user's finger. The inner or other end of the trigger is bifurcated to form two downwardly extending arms 32 the lower ends of which are adapted to engage the underlying portion 14' of rim 14 of the container top on opposite sides of depressed portion 24 of the cover member. Longitudinal movement of the trigger into the cover is prevented by a curved part 34 of the trigger between the main body of the trigger and finger engaging end 31 thereof. This curved portion engages the upper edge 35 of opening 28 in the cover member. To prevent removal of the trigger through the opening 28 or substantial longitudinal movement of the trigger in that direction whereby the arms 32 might become disengaged from the underlying portion 14', a portion 36 of the trigger is bent downwardly and is sufficiently long to extend below the lower edge of opening 28, even when the trigger is in its uppermost position.

As will have already been surmised the trigger extends diametrically across the top of the discharge valve and, therefore, across flexible diaphragm 18. It is provided with a depressed portion 37 intermediate its ends which engages diaphragm 18. Upon depression of the finger engaging end 31 of the trigger, the trigger pivots downwardly about the vertically confined inner arms 32 thereof, depressing the valve actuating member or button (not shown) through flexible diaphragm 18 to open the discharge valve and permit the discharge of the container contents through nozzle 20. Because of the leverage involved, operation of the attachment is relatively easy and non-fatiguing and therefore it is a simple matter to operate the discharge valve and any degree of opening of the valve may be easily and readily accomplished. When the finger engaging end of the trigger is released, the trigger is moved upwardly by the diaphragm and valve-actuating member of the discharge valve under the urging of a spring (not shown) incorporated

in the valve mechanism and under the pressure of the container contents.

The modified form of trigger 33 disclosed in Fig. 4 is in most respects similar to that shown in Figs. 1-3. The main difference in it is that it is provided at its inner end with a reverse transverse bend 39 the lower end of which engages flange 17 of the discharge valve and the upper end of which lies in close proximity or in engagement with the cover member. Because part 26 of the depressed portion of the cover lies in close proximity to the wall of the discharge valve the inner end 39 of the trigger is fairly well confined and is prevented from slipping off the flange of the discharge valve.

The operation of the attachment of Fig. 4 is the same as that of the preferred form except that the inner end 39 of this trigger is vertically confined by the cover member rather than by rim 14 of container top 13 as was the previously described form.

Either valve-actuating trigger attachment, as will be apparent from the above description, may be inexpensively manufactured as both of its parts, namely, the cover member and the trigger may be formed by simple stamping operations. By suitable modifications in the shape of the cover member, and if necessary in the shape of the trigger, an attachment may be made for any type of pressure-tight container having a discharge valve, a portion of which extends above the container and which is adapted to be operated by the application of pressure to its top.

I claim:

1. A valve-actuating trigger attachment for a pressure-tight container provided with a self-contained discharge valve, the upper portion of which extends above the top of the container, the discharge valve being of a type which is opened by the application of pressure to its top and discharges through a discharge nozzle, comprising a cover member adapted to be removably secured to the top of the container over the discharge valve and having an opening therein through which the nozzle may discharge, and a trigger freely mounted within the cover member and adapted when the attachment is in place on a container to extend across and normally in contact with the top of the discharge valve, one end of the trigger extending through a second opening in the cover member whereby the trigger may be engaged by a user's finger and moved to valve opening position, the inner end of the trigger being adapted to rest, when the attachment is secured to the top of a container, beneath an immovable rim on the top of the container and surrounding the discharge valve, and the inner end of the trigger being prevented by said rim of the container top from moving a substantial distance in a vertical direction.

2. A valve-actuating trigger attachment for a pressure-tight container provided with a self-contained discharge valve the upper portion of which extends above the top of the container, the discharge valve being of a type which is opened by the application of pressure to its top and discharges through a discharge nozzle, comprising a cover member adapted to be removably secured to the top of the container over the discharge valve and having an opening therein through which the nozzle may discharge, and a trigger freely mounted within the cover member and adapted when the attachment is in place on a container to extend across and normally in contact with the top of the discharge valve, one

end of the trigger extending through a second opening in the cover member whereby the trigger may be engaged by a user's finger and moved to valve opening position, the inner end of the trigger being bifurcated and the arms of the bifurcated end lying one on either side of the discharge nozzle and having their lower ends engageable with an underlying portion of a rim on the top of the container.

3. A valve-actuating trigger attachment for a pressure-tight container provided with a self-contained discharge valve the upper portion of which extends above the top of the container, the discharge valve being of a type which may be opened by the application of manual pressure directly to its top and discharges through a discharge nozzle, consisting of a cover member removably securable by a tight fit to the top of the container over the discharge valve and having an opening therein through which the nozzle may discharge, a trigger freely supported within the cover member and adapted when the attachment is in place on a container to extend across and normally in contact with the top of the discharge valve and to be movable thereagainst to open the valve, one end of the trigger extending through a second opening in the cover member whereby the trigger may be engaged by a user's finger and moved to valve opening position.

4. A valve-actuating trigger attachment according to claim 3 in which a portion of the trig-

ger within the cover is bent downwardly from the remainder thereof to prevent removal of the trigger through the opening in the cover member through which said one end of the trigger extends.

5. A valve-actuating trigger attachment according to claim 3 in which the inner end of the trigger is adapted to rest, when the attachment is secured to the top of a container, upon a portion of the discharge valve of the container which is immovable and in which said inner end of the trigger is prevented by the inner face thereover of the cover member from moving a substantial distance in a vertical direction.

6. A valve-actuating trigger attachment according to claim 3 in which the cover member is dome-shaped and in which said cover has a first depression therein surrounding said opening through which the nozzle may discharge and a second depression therein surrounding said opening through which said trigger extends.
